UNITED STATES PATENT OFFICE.

JOSEPH DE FRANCISCI, OF BROOKLYN, NEW YORK.

MACARONI PRESS.

Application filed December 1, 1921. Serial No. 519,108.

To all whom it may concern:

Be it known that I, JOSEPH DE FRANCISCI, a citizen of the United States, residing at the city of New York, borough of Brooklyn, 5 county of Kings, and State of New York, have invented a certain new and useful Macaroni Press, of which the following is a specification.

This invention is a press including hydraulic mechanism for imparting movement 10 to a plunger operating within a cylinder and co-operating with an expressing die.

The invention is adapted, more particularly, for the production of macaroni, 15 though the mechanism as a whole or parts thereof may be used in other industries.

One object of the invention is to secure a tight connection between a plunger cylinder and a detachable head for said cylinder with 20 a view to precluding leakage of the fluid supplied under hydraulic pressure for the power stroke of the press plunger.

A further object is to provide a novel valve mechanism which performs the functions of controlling the fluid under pressure to one side or the other of the press plunger and to control the return flow of such fluid to the pump mechanism, an important feature of said valve mechanism being to release the pressure through the valve in a simple and facile manner prior to the actual reversal of said valve for effecting the control of the fluid under pressure and the return flow of said fluid.

35 A further object is to lock the valve actuator and to release the same by fluid pressure means as the plunger moves in the direction of its effective stroke.

A further object is to lock the dough cylinders in alignment with the plunger cylinder to the end that there will be no relative movement of one cylinder to the other at the beginning of the effective stroke of the plunger or during the travel of said 45 plunger.

According to this invention, the plunger cylinder is provided with an external solid collar adjacent the outer (upper) end thereof, and on this end of said cylinder is fitted 50 a detachable cylinder head, a compressible packing being interposed between cylinder and head. Co-operating with the head is a clamp in the form of a ring composed of separable parts bolted solidly together, said 55 annular clamp being provided with a flange

or lugs adapted to fit snugly to the under side of the cylinder collar so as to interlock therewith. The annular clamp carries a number of binding screws adapted for contact with the cylinder head. These screws 60 are tightened against the head for compressing the gasket, and the pressure of the screws is resisted by the flange or lugs of the clamp in engagement with the cylinder collar, whereby I am enabled to obviate the elongation of the ordinary stud bolts under the hydraulic pressure and to retain the head in such tight relation to the cylinder as to effectually preclude leakage of the motive fluid.

The controlling valve includes a valve shell provided with a cylindrical bore and a tapering seat, adapted to receive the stem and conical head of a rotatable valve, whereby the valve is mounted in the shell to utilize the pressure in retaining the valve to its seat, as a result of which leakage is precluded. The several pipes are connected to the valve shell for the purpose of feeding the fluid under pressure to the valve, of returning the fluid to the pump, of feeding the pressure from the valve to the plunger cylinder, and of returning the fluid from the said cylinder to the valve. To this end, the valve is constructed with feed channels and ports and with a return channel and ports, whereas the valve shell is formed with a pressure chamber and with the required fluid passages to open into the cylinder pipes and the return pump pipe, said single valve 90 being operable to direct the motive fluid from the pump to one end or the other of the plunger cylinder as well as to provide for the flow of the fluid from the pressure cylinder to the return pump pipe.

An important feature of the valve mechanism consists of means for relieving the valve from the pressure of the motive fluid prior to the rotative movement of said valve, whereby the manual operation of said valve 100 is rendered capable of easy performance. To this end, the valve shell is provided with a by-pass leading from the pressure chamber to a bonnet valve which is seated within said valve shell at a point in the return circuit, and with this bonnet valve co-operates a valve lifting cam forming a part of a bushing rotatably fitted on the stem of the rotatable valve. With the bushing is combined a lever member provided with a 110

plurality of studs, and to this lever member is connected a link which is attached to a lever adapted to be operated by fluid pressure so that as the press plunger descends 5 and approaches the end of its effective stroke the bushing and cam will be partially rotated for lifting the bonnet valve so as to relieve the valve from the pressure of the motive fluid prior to the manual rotation of said valve. Co-operating with the studs of the lever member is a valve actuator attached to the stem of the valve so that the operator is enabled, subsequent to the release of the pressure by the bonnet valve, to shift the 10 valve in one direction or the other for reversing the direction of flow of the motive fluid to and from the plunger cylinder. The rocking movement of the valve and the valve actuator is arrested by suitable stops in the 15 path of said actuator.

A further feature of the invention is a locking contrivance for the dough cylinder in order to align it with the press cylinder, comprising a latch slidably fitted to the press frame and co-operating with notched arms on the dough cylinders. Said latch is held in an operative position by spring pressure, and it is held in a retracted position by a 20 detent.

30 Other functions and advantages of the invention will appear from the following description taken in connection with the accompanying drawings, wherein—

Figure 1 is a side elevation of a press especially adapted for the manufacture of 35 macaroni, illustrating an hydraulically operated plunger cylinder in vertical section.

Figure 2 is a plan view of the plunger cylinder.

40 Figure 3 is an enlarged view in side elevation of the controlling valve and the actuating means therefor.

Figure 4 is a cross section on the line 4-4 of Figure 3.

45 Figure 5 is a transverse section on the line 5-5 of Figure 4.

Figure 6 is a detailed plan view of the 50 rocking valve removed from the valve casting.

Figure 7 is a cross section through the valve in the plane of the dotted line 7-7 of Figure 9, showing the valve in a position for controlling the flow of fluid to one 55 end of the cylinder and the return of fluid from the other end of the cylinder to the valve.

Figure 8 is a view similar to Figure 7 showing the valve in a reverse position.

Figure 9 is a longitudinal section through 60 a part of the valve member in a position for permitting the flow of the fluid under pressure from the pump into one of the pipes leading from the plunger cylinder.

Figure 10 is another detailed longitudinal 65 view through the valve mechanism showing

the ports in the rocking valve positioned for the return flow of the liquid from the plunger cylinder to the return pump connections.

Figure 11 is a cross section through the 70 valve mechanism on the line 11-11 of Figure 4 illustrating the bonnet valve in an open position.

Figure 12 is a cross section similar to Figure 11 showing the bonnet valve in a 75 closed position.

Mounted in the press frame A of suitable construction, is a plunger cylinder B within which operates a plunger C, the diameter of which is slightly less than the internal 80 diameter of the plunger cylinder so as to leave an intermediate space c. At its upper end the plunger is provided with a piston head b and with packings b' b² of any suitable character. At its lower end the plunger is provided with a flange c⁴, with which co-operates means to be hereinafter described for shifting the valve mechanism so as to release the pressure on the turning plug of 85 said valve. The upper end of the cylinder is closed by a head D adapted to be clamped by novel means constituting a part of my invention. The cylinder is provided at its upper end with an external flange e extending outwardly from the cylinder wall, and between the cylinder wall and the head is positioned a compressible gasket f adapted to produce a liquid tight connection between the cylinder wall and the head so as to effectually preclude the leakage of the motive 90 fluid supplied under the required pressure to the end of the cylinder in forcing the plunger downwardly with an effective stroke. One of the improvements which I have made consists of means for clamping 95 the head D upon the cylinder in a way to resist the hydraulic pressure supplied to the cylinder between the piston head of the plunger and the removable cylinder head D.

E designates a clamp composed of complementary sections E' E² provided with radial flanges e' and assembled in abutting relation so as to be secured solidly together by transverse bolts e², as shown more clearly in Figure 2. The annular clamp is of 100 separable construction for ready assemblage with respect to the upper end of the cylinder, an essential feature of the annular clamp consisting of the inwardly extending flange g provided on the lower edge of the 105 clamp and adapted for engagement with the under face of the external shoulder e provided on the cylinder. The annular clamp carries a series of set screws or stud bolts G which are screwed into threaded bores provided in the clamp, said set screws or stud 110 bolts being adapted to be tightened against the head D for the purpose of drawing the flange g of the clamp into tight engagement with the external shoulder of the cylinder. 115

120

125

130

It will be noted that the stud bolts G press downwardly upon the cylinder head and draw upwardly on the annular clamp, whereby the flange g of the clamp has a firm bearing against the cylinder shoulder, and the head D is forced downwardly toward the cylinder for compressing the gasket f in order to secure the necessary liquid tight connection between the cylinder and its head.

5 In my invention the stud bolts G are not subjected to elongated strain under hydraulic pressure admitted to the cylinder, and thus the stud bolts serve as an efficient means for holding the cylinder head in tight engagement with the cylinder for precluding leakage of the hydraulic pressure. The lower end of the plunger cylinder is open so that the plunger or ram C may travel therein; but the motive fluid is precluded 10 from leaking from the open lower end of said plunger cylinder by a packing c' positioned within a recess provided in the cylinder wall, as shown in Figure 1. This packing is compressed around the plunger by a gland C' secured to the end face of the cylinder by stud bolts c², said packing c' being of a form commonly used in the art so as to be expanded by the pressure of the motive fluid in order to secure the necessary contact with the plunger or ram.

15 F F' are the dough cylinders coupled together at f' and fitted on one of the press columns to rest upon collars f², so that the dough cylinders are free to turn on the press columns for the purpose of positioning one dough cylinder or the other into alignment vertically with the hydraulic cylinder B. It will be understood that each dough cylinder is open at the upper end and provided 20 in the lower end with an expressing die, as is usual in the art. Furthermore, each dough cylinder is provided with an outwardly extending arm g' adapted to fit around one of the press columns when said cylinder is in alignment with the hydraulic cylinder, each of the arms g' being provided with a notch g² adapted to be engaged by a latch G'. This latch is shown in Figure 1 as being slidably mounted in keepers g³, and 25 said latch is adapted to enter one notch g² for locking the dough cylinder in aligned relation with the hydraulic cylinder. The latch is retained in an elevated operative position by a spring g⁴ acting on the lower 30 end of a rod g⁵, having a head g⁶ which enters one of the notches g⁷ provided in said latch. When the latch is withdrawn, a detent G² enters one of the notches g⁷ for locking the latch in a retracted position, 35 thus holding the latch out of the path of the notched arm g' upon the rotative movement of the dough cylinders.

Referring now to the valve mechanism, H designates a valve shell and I a rotating plug or valve member. As shown more particu-

larly in Figures 4, 9 and 10, the valve shell is provided with a bore h which is enlarged and made tapering at one end as at h' so as to form a seat, the bore h being enlarged toward the other end so as to result in a shoulder h² and to produce a chamber h³ for the motive fluid returning from the plunger cylinder to the pump. The valve shell is open at one end as at j to receive a closure plug J adapted to be screwed into the open end j, said plug being provided with an external shoulder j' and with a squared lug j². The lug is adapted to receive a wrench or other implement for screwing the plug tightly into the valve shell, and between the shoulder j' of the plug and the valve shell is interposed a gasket j³ which is compressed by the operation of screwing on the plug so as to secure a water tight joint between the valve shell and the closure plug.

85 The valve plug I consists of a cylindrical stem i and a conical head i' with a flat end face, see Figures 4, 6, 9 and 10. The cylindrical stem of the valve is made polygonal or angular in cross section as at i² and the end of this stem is reduced and threaded as at i³. The conical head i' of the valve is provided with a plurality of fluid passages k k' terminating in ports k² k³, respectively. In addition to the passages k k' 95 said valve is provided with a longitudinal passage l which opens at one end so as to form a port l' and the other end of which passage l opens in an opposite direction so as to form a port l², the passage l and the port l² being indicated by dotted lines in Figure 6 and in full lines in Figures 4 and 10.

100 The rotating valve plug I is positioned within the parts h h' h³ for the cylindrical stem i to occupy bore h and extend across the chamber h³, whereas the conical head i' of the valve is positioned within a conical seat h' of the shell in such relation that the flat end face of the valve plug is spaced 105 relatively to the end wall of the valve casting and the closure plug J, as a result of which relative spacing there is provided a pressure chamber K within the valve shell and intermediate the plug J and the flat end face of the valve head i', see Figures 4, 9 and 10.

110 A pressure pipe L leads from the pump or accumulator to the valve shell H and is connected fixedly thereto for direct connection with the pressure chamber K. Return pipe M leads from the valve mechanism to 115 the pump, said pipe M being coupled to the valve shell H for direct connection with the return chamber h³.

120 From the valve shell two pipes N O extend to the plunger cylinder B, said pipe N leading to the upper end of the plunger cylinder B and connected directly thereto at a point below the cylinder head D, whereas the pipe O is connected with the plunger cylinder for connection with the narrow an-

nular space c normally existing between cylinder B and the plunger, as shown in Figure 1.

The lower end of the pipe N is in communication with a fluid passage n provided in the valve shell H so as to open at a certain point into the conical seat h' . In a similar manner, the lower end of the other pipe O is attached to the valve shell H for free communication with the fluid passage o which is provided in the valve shell H so as to open into conical valve seat h' , the two passages n o terminating in ports which are spaced relatively to each other. The valve plug I is rotatable within the valve shell so that its feed ports k^2 k^3 are adapted for connection with passages n o , respectively. It will be understood that the valve plug I may be turned to the position of Figure 8 in order to bring the port k^3 of passage k' into register with the port n of pipe N, and at the same time the port l' of passage l is in register with the port o of pipe O. With the parts in the described position the motive fluid under pressure is free to pass from chamber K through the passage k' and port k^3 of the valve plug into the port n and thence to the pipe N for admitting the motive fluid to the upper end of the plunger cylinder whereby the plunger is forced downward with the required force, and at the same time the fluid previously admitted to the space c existing between the plunger and the cylinder is free to pass through the pipe O and its port o into the passage l of the valve and thence to the chamber h^3 of the valve shell so that the returning motive fluid will pass through the pipe M back to the pump. For reversing the operation, the valve plug is turned in the manner herein-after explained to occupy the position in Figure 7 wherein the port k of the valve is in register with the port o of pipe O, and the port of passage l of said valve plug is in register with the port n of valve shell H. The motive fluid under pressure passes from the chamber K through the passage k to the port k^2 and thence through the port o into the pipe O admitting the motive fluid to the space c between the plunger and the cylinder for the purpose of applying pressure to the under side of the plunger head in order to raise said plunger within the cylinder, and at the same time the fluid previously admitted to the upper part of the cylinder is free to pass through the pipe N and port n into the passage l of the valve, thence flowing into the chamber h^3 and through the return pipe M back to the pump. It will be observed that the flat end face of the valve head is exposed to pressure of the motive fluid supplied from the pump by the pipe L to the chamber K, thus forcing the conical head of the valve into such tight engagement with seat h' as to preclude leak-

age from the valve; but owing to the pressure of the motive fluid directly upon the end of the valve, it becomes difficult to rotate the valve in order to control the flow of the pressure to one pipe or the other, N O. With a view to overcoming this objection, and rendering easy the operation of reversing the valve plug, I provide means for relieving the valve plug from the pressure of the motive fluid. To this end, a by-pass p is provided in the valve shell H, one end of the by-pass passage opening into the pressure chamber K. Said by-pass is in free communication with chamber p' , the bottom of which constitutes a seat p^2 for a bonnet valve P, said chamber p' opening into a port q which is in free communication with the return chamber h^3 . The upper part of the chamber p' is closed by a plug P' adapted to unscrew for obtaining access to the bonnet valve. Said bonnet valve is exposed to the pressure of the motive fluid admitted to the chamber K and admitted also through the by-pass p to the chamber p' , whereby the pressure holds the bonnet valve to its seat.

Means are provided for lifting the bonnet valve in order to open a path for the motive fluid from the by-pass p to the return chamber h^3 , said means consisting of a valve lifting cam Q of angular form in cross section, as shown in Figures 11 and 12. This valve lifting cam is provided at the inner end of a bushing Q', which is rotatably fitted on the cylindrical part i of the rocking valve, the valve lifting cam Q constituting an unitary part of the bushing Q'. Said valve lifting cam is provided with a curved face q^2 which is fitted snugly on the cylindrical stem i of the valve, and the bushing Q' is fitted into the chamber h^3 and loosely encircles the valve stem i so that the bushing will turn on the valve stem and within the chamber h^3 . The bushing extends beyond the end of the valve shell opposite to the plug J, said bushing being unitary with a plate member Q² which is provided with an outwardly extending lever arm R. To the lever arm is pivoted the lower end of a link r by pivotal connection r', said link r extending upwardly to a suitable operating device in the form of a lever R'. This lever is fulcrumed at r^2 on one of the press columns and the inner end portion of the lever being in the path of the flange c⁴ at the lower end of the press plunger, whereby on the upward movement of the press plunger the flange c⁴ lifts the inner end of the lever R' and depresses the rod r so as to turn the lever R and rotate the bushing Q', thereby moving the valve lifter Q in a direction to lift the bonnet valve and release the pressure of the motive fluid against the flat end face of the conical head forming a part of the valve plug. Upon the descent of the plunger and as it approaches the lower limit of its travel,

the motive fluid confined within the annular space c is free to pass through the port t into the chamber t' within which chamber operates a piston T , the stem t^2 of which is in contact with the inner end of the lever R' , whereby on the downward movement of the plunger C some of the motive fluid passes through the port t and acts upon the piston T for depressing the latter, the effect of which is to force downward the inner end of the lever R' , thus lifting rod r and the lever R so as to turn the bushing Q' and the valve lifter Q in an opposite direction, thereby opening the bonnet valve to release the pressure on the end face of the valve plug I .

Means are provided for rocking the valve plug I by the movement of the lever R . On the squared part i^2 of the valve stem is fitted a valve actuator U in the form of a plate, said actuator being held fixedly on the stem of the valve plug by a washer u engaged by a spring washer u' which is in turn held by a nut u^2 screwed on the threaded end i^3 of the valve stem. This valve actuator is spaced relatively to the disk member Q^2 of the bushing and the lever arm by collars v , see Figure 4. The plate member Q^2 of the bushing and lever is provided with studs or pins $w w'$ which are made fast with the plate member Q^2 and positioned on opposite sides of the valve actuator U adjacent one end of the latter. The movement of the valve actuator is arrested in one direction or the other by stop pins $x x'$ attached to the valve shell H and positioned in the path of the valve actuator U at the other end thereof, see Figure 3. When the lever R is lifted to turn the plate member Q^2 and the bushing, the stud w engages with one end of the actuator U for the purpose of turning the valve I in its seat within the valve shell; but when the lever R is forced downward the other stud w' is brought into contact with the valve actuator U for the purpose of rocking the valve I in an opposite direction within the seat. It will be noted that the lever R is moved for a limited distance to unseat the bonnet valve and release the pressure on the plug valve before its stud w or w' contacts with the valve actuator, which contact of the stud with the valve actuator imparts a rotative movement to the plug valve, the effect of which is to relieve the pressure before the turning movement is given to the plug valve. This release of the pressure enables the plug valve to be turned easily, and there is thus a successive operation of the plug valve to the bonnet valve, although the operation of the two parts takes place from practically the same element; to-wit, the lever R .

The operation may be summarized as follows: With the plunger in the elevated position as shown in Figure 1, the valve plug I is in the position of Figure 8, so that the motive fluid supplied by the pipe L to the

chamber K will pass through the feed passage k' and port k^3 of the valve into the port n and thence through the pipe N to the upper end of the cylinder, and at the same time the pressure from chamber K flows through the by-pass p so as to hold the bonnet valve P in the closed position of Figure 12, any of the liquid present in the annular space c between the plunger and the cylinder being free to return through the pipe O and the port o into the passage l of the valve plug, thence to the chamber h^3 and by pipe M back to the pump. The continued supply of the motive fluid to the upper end of the cylinder forces the plunger downward at the required speed for expelling the material within one of the dough cylinders through the die; but as the plunger approaches the limit of its lower movement some of the motive fluid present in the space c flows into the chamber t' and depresses the piston T , the effect of which is to depress the inner end of the lever R' , thus lifting the rod r and the lever R . As the lever is raised the bushing Q' and the cam Q are turned to lift the bonnet valve, thus opening the by-pass for the motive fluid to pass from the chamber K into chamber h^3 , this opening of the bonnet valve and the release of the pressure taking place before the stud w contacts with the valve actuator U . As the lever continues to be lifted, stud w turns the valve actuator and rotates the valve plug I so as to change the relation of the ports $k^2 k^3$ from the position of Figure 8 to that of Figure 7. The port k of the valve plug is now in register with the port o of the pipe O for feeding the motive fluid under pressure to the lower end of the cylinder, forcing the plunger upward, the bonnet valve being closed. The liquid in the cylinder above the plunger flows through the pipe N and its port n into the passage l of the valve, thence flowing through the chamber h^3 from the pipe M back to the pump. As the plunger approaches the upper limit of its movement in the cylinder, the flange c^4 engages lever R' to depress the lever R through link r , thus moving the cam lifter to open the bonnet valve and release the pressure on the plug valve before the stud w' contacts with the valve actuator U for rotating the plug valve so as to reverse its position within the valve shell H .

Having thus fully described the invention, what I claim as new and desire to secure by Letters Patent is:

1. In an apparatus of the class described, the combination with a plunger cylinder, and means for feeding a motive fluid thereto, of a controlling valve positioned in the line of flow of the motive fluid, and arranged for its movable part to be held to a seat by the pressure of said motive fluid,

and plunger operated means for relieving said moving valve part from the pressure of the motive fluid.

2. In an apparatus of the class described, 5 the combination with a plunger cylinder, and means for feeding a motive fluid thereto, of a controlling valve positioned in the line of flow of the motive fluid, said valve including a rotatable part exposed to the 10 pressure of said motive fluid, a relief valve in a by-pass whereby the rotatable valve part is freed from the pressure of the motive fluid, and plunger operated means for operating the relief valve.
3. In an apparatus of the class described, 15 the combination with a plunger cylinder, and means for feeding a motive fluid thereto, of a controlling valve positioned in the line of flow of the motive fluid, said valve including a rotatable valve member 20 exposed to the pressure of the motive fluid, and an automatically operated relief valve whereby the rotatable valve member is made free from the pressure of the motive fluid.
4. In an apparatus of the class described, 25 the combination with a plunger cylinder, a plunger, and means for feeding a motive fluid to said cylinder, of a controlling valve positioned in the line of flow of the motive 30 fluid, said controlling valve including a member exposed to the pressure of the motive fluid, and means controllable by the movement of said plunger for relieving the movable valve part from the pressure of 35 the motive fluid.

5. In an apparatus of the class described, 40 valve mechanism for controlling the flow of a motive fluid relatively to a plunger cylinder embodying a casing provided with pressure connections and cylinder connec- 45 tions, a rotatable member seated in said casing and exposed to the pressure of the motive fluid, a valved by-pass in communication with the line of pressure, and pressure actuated means for operating said valve in the by-pass.

6. In an apparatus of the class described, 50 valve mechanism for controlling the flow of a motive fluid relatively to a plunger cylinder embodying a casing provided with a pressure chamber and with a by-pass, a rotatable valve part seated in said casing exposed to the pressure of the motive fluid, a relief valve seated in the by-pass, and 55 valve actuating means rockable on the rotatable valve part for unseating said relief valve.

7. In an apparatus of the class described, 60 valve mechanism for controlling the flow of a motive fluid relatively to a plunger cylinder embodying a casing provided with a pressure chamber, a valve member seated in said casing and exposed to the pressure of motive fluid in the chamber, a bon- 65 net valve, and means for operating said

bonnet valve to relieve the first named valve member from the pressure of said motive fluid, said bonnet valve actuator being rockable with the valve member as its axis of motion.

8. In an apparatus of the class described, 70 valve mechanism for controlling the flow of a motive fluid relatively to a plunger cylinder embodying a casing, a movable valve member exposed to the pressure of the motive fluid, a relief valve positioned to open a path for the flow of the motive fluid so as to relieve the movable valve member from said motive fluid pressure, and plunger controlled means for successively operating said relief valve and the movable valve member.

9. In an apparatus of the class described, 75 valve mechanism for controlling the flow of a motive fluid relatively to a plunger cylinder embodying a casing, a rotatable valve member seated therein, a reciprocable relief valve positioned to open a path for the flow of the motive fluid for relieving the rotatable valve member from the motive 90 fluid pressure, operating means for the relief valve, and operating means for the rotatable valve member.

10. In an apparatus of the class described, 95 valve mechanism for controlling the flow of a motive fluid relatively to a plunger cylinder embodying a casing, a rotatable valve member seated therein, a relief valve positioned to open a path for the flow of the motive fluid, and operating 100 means co-operating with the valve member and the relief valve for unseating the relief valve prior to shifting said valve member.

11. In an apparatus of the class described, 105 valve mechanism for controlling the flow of a motive fluid relatively to a plunger cylinder embodying a casing, a rotatable valve member exposed to the pressure of the motive fluid and normally held 110 to its seat thereby, a relief valve, and operating means for said rotatable valve member and said relief valve.

12. In an apparatus of the class described, 115 valve mechanism for controlling the flow of a motive fluid relatively to a plunger cylinder embodying a casing provided with a by-pass intermediate a pressure chamber and a return chamber, a rotatable valve member seated in the casing for exposure 120 within the pressure chamber, a bonnet valve seated in the by-pass intermediate said chambers, and means for operating the valve member and the bonnet valve.

13. In an apparatus of the class described, 125 valve mechanism for controlling the flow of a motive fluid relatively to a plunger cylinder embodying a casing provided with a by-pass, a relief valve positioned in the by-pass and seated by the pres- 130

sure of the motive fluid, a valve member seated in the casing, pressure operated means for unseating the relief valve, and means for operating said valve member.

5 14. In an apparatus of the class described, valve mechanism for controlling the flow of a motive fluid relatively to a plunger cylinder embodying a casing provided with a by-pass intermediate a pressure chamber and a return chamber, a relief valve positioned in said by-pass, a rotatable valve member seated in the casing, a bushing rotatably fitted to the valve member, a cam operated by the bushing and co-operating with said relief valve, and operating means for said valve member and the bushing.

10 15. In an apparatus of the class described, valve mechanism for controlling the flow of a motive fluid relatively to a plunger cylinder embodying a casing provided with a by-pass intermediate a pressure chamber and return chamber, a relief valve positioned in said by-pass, a rotatable valve member seated in the casing, a valve cam turnable on the valve member and co-operating with said relief valve, and operating means for said valve lifting cam.

15 16. In an apparatus of the class described, valve mechanism for controlling the flow of a motive fluid relatively to a plunger cylinder embodying a casing provided with a by-pass intermediate a pressure chamber and a return chamber, a relief valve positioned in said by-pass, a rotatable valve member seated in the casing, a bush-

ing rotatably fitted to the valve member, a cam operated by the bushing and co-operating with said relief valve, a lever movable with said bushing, a valve-actuator fast 40 with valve-member, and means operated by the movement of the lever for imparting rocking movement to the valve member.

17. In an apparatus of the class described, valve mechanism for controlling 45 the flow of a motive fluid relatively to a plunger cylinder embodying a casing provided with a pressure chamber and with ports for the flow of the motive fluid, a valve member provided with a conical head 50 seated in the casing and exposed to the motive fluid, said valve head having fluid passages and ports adapted for registration with the ports of the casing, a relief valve, and operating means for the relief valve 55 and said valve member.

18. In an apparatus of the class described, a plunger cylinder, a plunger, valve mechanism for controlling the flow of the motive fluid relatively to the plunger cylinder, a relief valve whereby the moving part of said valve mechanism is made free from the pressure of the motive fluid, and means operated by the movement of the plunger in one direction for effecting a successive 60 operation of the relief valve and the moving part of said valve mechanism.

In testimony whereof I have hereto signed my name this 30th day of November, 1921.

JOSEPH DE FRANCISCI.
